ABSTRACT

A pulsating plasma device is disclosed having a cylindrical plasma column and a pair of field exciter members disposed in spaced parallel relationship to the plasma column. Means are also provided for creating an electrostatic field through which oscillating energy is transferred between the plasma column and the field exciter members.

PULSATING PLASMA DEVICE

RELATED APPLICATIONS

The present application is a continuation-in-part of my prior application, Ser. No. 75,045 filed Sept. 24, 1970, now abandoned, which is a continuation-in-part of application, Ser. No. 840,087, filed June 2, 1969, now abandoned, which is a continuation-in-part of application, Ser. No. 408,464 filed Oct. 29, 1964, now abandoned.

SUMMARY OF THE INVENTION

The present invention relates to utilization of the normal modes of vibration of radial, angular, or axial motion of a non-uniform plasma or of a non-uniform electron gas in a plasma. The illustrated embodiment of the invention utilizes electron gas in a cylindrical plasma column, in conjunction with a pair of field exciter members which are coupled to the plasma column through a periodic electrostatic field, so as to operate as a plasma antenna. A second device is of the plasma type and utilized for controlling nuclear fusion at resonant frequencies, operating with a periodic magnetic field. Despite their differences the two devices are generally referred to as "pulsating plasma device."

In the prior art there has been considerable difficulty experienced in predicting the natural resonant frequency of an oscillating plasma column, and there has also been considerable difficulty experienced in determining the proper design of field exciter members for achieving maximum power transfer through the associated electric or magnetic field to or from the plasma column itself, in the number and location and configuration of the field exciter members, and in the nature of the field through which energy transfer is achieved, the underlying design problem has been that of analyzing the fundamental physical characteristics in order to be able to properly predict their mode of operation. The mathematical theory set forth herein is of a general nature and applies equally well whether the energy transfer is through an electric field or through a magnetic field. Where either an electric or magnetic field is meant, the term "force field" is used. The theory is also equally applicable whether the number of field exciter members is one or more than one, and regardless of their location and configuration.

Thus, the general object of the present invention is to provide a new and improved pulsating plasma device. The more specific object of the invention is to provide an improved pulsating plasma device in which the number, location and configuration of one or more field exciter members is so selected as to be in conformity to the existing characteristics of the plasma column, whereby maximum energy transfer may be achieved between the field exciter member(s) and the plasma column.

For several years it has been found by experimenters that the positive column of a discharge tube has many more resonant frequencies than the one predicted by the usual theory of such devices, namely, the plasma or Langmuir frequency. In my invention I utilize a more complete understanding of the phenomenon in order to achieve a more efficient device. It is well-known that an important current problem in the control of thermonuclear reactions in a plasma is the stabilization of operation so as to prevent unwanted oscillations and unwanted plasma waves from destroying confinement. At

the same time an important objective is to operate the devices so as to achieve high temperatures and pressures. In my invention I utilize the plasma waves to enhance the energy transfer, and to stabilize the motion at a desired frequency.

DRAWING SUMMARY

FIG. 1 is a perspective view of a plasma antenna incorporating my invention;

FIG. 2 is a cross-sectional view of the device taken on the line 2-2 of FIG. 1;

FIG. 3 is a cross-sectional view of the device taken on the line 3-3 of FIG. 2; and

FIGS. 4a and 4b are isometric and end views respectively of the plasma fusion device.

PREFERRED EMBODIMENT

In the drawing a glass tube 2 having a cylindrical interior configuration contains a continuous positive discharge column, and a sphere or bulb 1 is attached to one end of a tube 2 in communication therewith for supplying a continuous mercury arc discharge to the tube 2. The lower portion of sphere or bulb 1 contains two separate recesses which receive respective electrodes 3a and 3b, each of these electrodes being surrounded by a separate mercury pool 4, as shown in drawing FIG. 2. Electrode 3a is connected to the positive terminal of an external battery E₂, typically of 15-volts potential, and terminal 3b is connected to the negative terminal of that battery which is also grounded. Electrodes 3a and 3b are not necessarily of the same configuration, because one may protrude upward and be bent over the other so as to provide a relatively narrow gap. The mercury arc discharge occurs continuously between the ends of the two electrodes, or between one electrode and the bath surrounding the other electrode. An electrode 5 is plugged into the other end of tube 2, and is also connected to the positive terminal of an external battery E₁, whose negative terminal is grounded. The potential of battery E₁ is typically 75 volts. Thus there is a constant potential difference between the two electrodes 3a and 3b of the bulb 1, and the electrode 5 is also maintained at a substantial positive potential relative to the bulb 1. This apparatus including the tube 2, sphere or bulb 1, electrodes 3a and 3b, mercury baths 4, electrode 5, and external batteries E₁ and E₂ is a conventional apparatus which is well-known and widely used for the purpose of establishing and maintaining a positive discharge column of cylindrical configuration.

In order to stabilize the natural resonant frequency of the plasma column a blower 11 is utilized, having an outlet opening 12 which is so positioned as to discharge cool air directly upon the full length of the tube 2. In this manner the plasma column is continuously cooled and its temperature maintained at a uniform level throughout the entire length of the column.

A wave guide 7 terminates a short distance from the electrode 5. The wave guide 7 has an internal opening 60 that is of rectangular configuration, and it is energized with an electromagnetic field at a microwave frequency, the exciting voltage E_e being aligned in the vertical direction and hence in the narrower dimension of the interior opening of the wave guide 7. The configuration and method of operation of wave guide 7 are entirely conventional.

Microwave energy from the wave guide 7 is supplied to the plasma column through the medium of a pair of

field exciter members 8. The members 8 have a substantial length, approximately equal to the length of tube 2, and are supported in spaced parallel relationship to the longitudinal axis of the plasma column. Insulating spacers 9 are utilized to support the two ends of members 8 in their proper spaced relationship, and at the same time a central hole or opening in each of the insulators 9 receives and supports the glass tube 2 so that the plasma column is mechanically supported in its proper position relative to the members 8. At one end the field exciter members 8 are physically attached to the upper and lower side walls, respectively, of the wave guide 7, in electrically conductive relationship thereto. As a result the vertically aligned exciting voltage E_t , furnished from the wave guide 7 is also present between the members 8, as is shown in drawing FIG. 3.

According to the invention each of the exciter members 8 has a substantial surface width in a direction generally transverse to the longitudinal axis of the plasma column. Furthermore, the inner surface of each exciter member faces toward the plasma column and is curved in a plane that is perpendicular to the longitudinal axis of the column. The curved characteristic of the inner surface of each field exciter member 8 is also constant throughout a substantial length of the member. An additional characteristic which is extremely important, in accordance with the present invention, is that the curvature and physical positioning of the exciter members 8 are so selected that the near, or so-called "force" field developed thereby is at least approximately proportional to the sine of m times the angle θ (in this case m is one). This relationship will be explained in a later section of this description.

In order to initiate the electron flow in tube 2 it is necessary to use a Tesla coil to break down the positive column, that being a conventional procedure.

When energy is supplied from wave guide 7 the device operates as an antenna, radiating energy outwardly from both sides of the plasma column as shown in FIG. 3. Specifically, the line P_1 shows the radiated or far field strength pattern, or lobe, on one side of the pair of members 8, and the curved line P_2 shows the radiated or far field pattern on the other side. The generated signal strength is symmetrical on both sides of the device. Vertical arrows E_t show the electric field polarization of the transmitted energy. The radiated field is proportional to $\cos m\theta$. (In the case illustrated m is one).

While the device illustrated in the drawings has been described as a transmitting antenna, it also operates as a receiving antenna with equal efficiency. In that event the energy is received from some external source and picked up between the exciter members 8, being then transmitted into the wave guide 7.

While the present drawing illustrates a particular manner for initiating and maintaining a cold cathode discharge in the tube 2, it will be understood that these details are conventional and of no particular interest insofar as the present invention is concerned, and as a matter of fact the present invention is equally applicable to a hot cathode discharge or any other type of discharge that may be available for purposes of providing a confined cylindrical plasma column.

More specifically, it will be understood that the significance of the present invention is limited to the cylindrical configuration of the plasma column within the tube 2, the natural resonant frequency of that plasma column, the number and location and configuration of the members 8, and to the intended mode of operation

of the plasma column and the members 8 in conjunction with each other.

Some specific characteristics of the illustrated embodiment of the invention are as follows. The length of the positive column is 45 centimeters and its inside diameter is 5.6 mm. The length of field exciter members 8 is approximately 50 centimeters, their radium of curvature is 1.9 cm., and the distance between the inner surfaces of members 8 is approximately 2.5 cm. Wave guide 7 is a standard C band wave guide. At a frequency of 4 GHz with cooling air at 75° F blowing over the tube, pure dipole resonances were found at currents of 375, 430, and 560 ma anode current. Coupling with axial modes was found at 700, 775, 830 and 925 ma. At a frequency of 5 GHz the dipole resonances were found at 515, 580, 925 ma, and others which were above the range of the measuring equipment. The resonant current for a given frequency is determined by both the temperature of the positive column and the temperature of the mercury reservoir, both of which must be controlled to control the resonant current. The power transmitted from the antenna at the main resonance for 4 GHz (560 ma) at a receiving horn on the plane of symmetry was approximately 6 db above the power transmitted with the discharge tube turned off.

A second embodiment of the invention is shown in FIG. 4 wherein a glass wall, 13, and a conductor 14 are shown in two views. Means are provided for introducing a gas into the glass cylinder and for pre-ionizing the gas to form the plasma in a conventional manner. The external electric circuits (not shown) are well-known in the art and are illustrated on page 9a of the publication by G. Decker, Report IPP 1/51, Institut fur Plasma-physik, Garching Bei Munchen, Sept. 1966. The plasma 15 is confined by the magnetic field formed by the current in conductor 14. The current in conductor 14 is caused to oscillate by an external circuit. The oscillation frequency is chosen as described below under the section entitled "Modified Scylla Device."

MATHEMATICAL THEORY OF THE DEVICE

The invention described herein consists of the combination of external electrical circuit, field exciter means, and a choice of plasma properties in order to more efficiently utilize the natural properties of the plasma.

A cylindrical plasma will not have a density which is uniform from the axis to the edge. Rather the density, in many cases of interest, follows more closely the mathematical curve known as a gaussian with a characteristic value (length) in the radial direction which is σ (the standard deviation). The gaussian curve is described mathematically by the function:

$$n = n_0 \exp[-r^2/2\sigma^2]$$

where n_0 is the number of particles per cc, on the axis of the plasma, r is the distance in meters from the axis.

If the ions and electrons are warm, they each have a temperature T_i and T_e , respectively. In addition, because each of the gases is compressible, there is a sound speed corresponding to each gas an acoustic wave phase velocity in the plasma: the ion acoustic wave phase velocity, C_i , and the same for the electrons, C_e .

However, the wave speeds are not simple expressions as in the usual expression for sound waves, but, involve, (1) the angular frequency ω (which is 2π times the oscillation frequency f), (2) the viscosity of the electron gas, ν_e , (3) the mass of the electron, m_e and the mass of an ion, m_i , and (4) the ratio of specific heats, γ_i and γ_e .

The expressions for C_i and C_e also include Boltzman's constant k , as follows:

$$(C_i)^2 = (\gamma_e k T_e + \gamma_i K T_i + 2\omega \nu_e m_e)/m_i$$

and

$$(C_e)^2 = \gamma_e k T_e / m_e + 2\omega \nu_e$$

Having a characteristic length σ , and a characteristic sound speed C , then it is easy to show on dimensional grounds that the ratio C/σ would give a frequency of oscillation which would be appropriate for the fundamental frequency of radial pulsations.

In a more detailed analysis, I have shown that this frequency would actually be $C/(\sqrt{2\pi\sigma})$. If ion oscillations are desired than one uses the frequency $C_i/(\sqrt{2\pi\sigma})$; if electron oscillations are desired then one uses the frequency $C_e/(\sqrt{2\pi\sigma})$.

In addition to the above frequencies there are many other resonances predicted and observed. These frequencies may depend on the spatial variation of the exciting field which is induced in the plasma by the coupling means.

For example the above frequency formula applies where the coupling means is a single exciter former from a cylindrical annulus, which is split along the longitudinal axis at one point. Such a device is shown in FIGS. 4a and 4b and also on page 71 of "Project Sherwood," by Amasa S. Bishop, Addison-Wesley Publishing Company, Inc., Reading, Massachusetts, U.S.A. 1958. On each side of the split the leads to the external electrical circuit are connected. In this case there is no variation either with angle or with the axis of the magnetic field generated by current flowing around the annulus, at least in the center of the annulus.

As a second example, if two properly designed parallel field exciter members are mounted parallel to the axis of a plasma column and on either side of it, and a potential difference applied between the field exciter members, then the azimuthal electric far field near the column will have an angular variation proportional to the cosine of the angle from the midplane which angle is denoted as Theta (θ). (See FIG. 3). If a larger and arbitrary number of excitors are used, the far field, which is perpendicular to the plane from the point to the axis, will be made proportional to cosine of m times θ , the angle, where m is an integer. The near field, which is along the radius from its point to the axis, would then be proportional to $\sin m\theta$.

Similarly, if one so desired, he could cut the two parallel field exciter members into a series of short field exciter members each insulated from its neighbors. By properly arranging the phase of the input to each field exciter member segment, the exciting field will have a variation in the axial direction proportional to $\cos(\pi p z/2L)$, where p is an integer, z is the distance along the column from the origin and L is the total length of the field exciter members.

If in the following I specify that m is three and p is two, for example, the man skilled in the art will know immediately how to arrange the field exciter members and their connections in order to accomplish the desired variation for the exciting field.

In addition to the design of the field exciter means, the external electric circuit should be designed or adjustable to operate at the resonant frequency of the plasma oscillations. Since either magnetic or electric coupling between two weakly coupled circuits will give maximum power transfer at resonance, provided both

circuits resonate or operate at the same frequency, the frequency of operation is obviously a critical design parameter.

The frequency of operation depends on m and p , as well as the plasma characteristics given previously. Thus, the man skilled in the art will need only to consult Table 1 for the resonant frequencies as a function of m and p in order to define the frequency which is to be used for a particular configuration of field exciter members.

The resonant frequencies, in general, are found through the solution of an eigenvalue equation, or resonance condition. As usual in such cases, there is a differential equation which defines the radial variation of the function which describes the radial motion. The solution of the differential equation for this problem is in general approximately proportional to ${}_1F_1(A, B, D)$, (which is the well-known confluent hypergeometric function). The values of B and D in this function are determined both by the values of the coefficients of the differential equation and by the radial distance, r_o , from the axis to the surface of the plasma. Then the value of A , (called the eigenvalue) is determined by solving the equation which arises when ${}_1F_1(A, B, D)$ is set equal to zero. Since B and D are given, A is the solution of a transcendental equation and may have several values, i.e., A_1, A_2, A_3 , etc., and any one of these particular values is referred to generally as A_i . At the same time, we have derived from the differential equation, a theoretical expression, or equation, for A which may be set equal to the above set of values of A , and solved for the set of resonant frequencies. These frequencies will then be used by the designer. Table 1 shows the resonant frequencies in terms of eigenvalues A_i and the particular plasma parameters. The check ($\checkmark$) mark indicates motion and the cross ($\times$) mark indicates no motion of the plasma in the R, θ, Z directions.

If in addition to the effects of previously mentioned variables, the electrons have a mean drift velocity; U , then the resonant frequencies may also be affected as will be shown by my formulas.

In addition it should be noted that if the plasma has a mean angular velocity about the axis denoted by the symbol Ω , the formula for the standard deviation σ , for a magnetically confined plasma is:

$$\sigma^2 = [\mu H^2/M - \Omega^2]^{-1} k T_i / m_i$$

where $\mu H^2/M$ must be greater than Ω^2 . $\mu H^2/2$ is the magnetic pressure at the surface of the plasma. $\mu H^2/2$, which stands for the magnetic pressure at the surface of the plasma, is a short-hand notation for the more general expression for the net inward stress on the plasma surface due to electric and magnetic fields. This general expression depends on the dielectric constant of free space, ϵ , and the electric field, E , and the component of E which is normal to the surface denoted as E_n . The net inward stress is determined by evaluating the following expression just outside the plasma, and just inside the plasma surface currents and charges, and finding the difference, i.e., $\mu H^2/2$ stands for $[(\epsilon E^2 + \mu H^2)/2 - \epsilon E_n^2]_{out} - [(\epsilon E^2 + \mu H^2/2 - \epsilon E_n^2)]_{in}$. We assume, no component of μH is normal to the surface. μ is the permeability of free space. M is the mass of the plasma per unit length. All units used are in the mks system.

The values of B and D are shown in Table 1. The frequency of resonance is given as a function of the type of motion in the plasma and the spatial variation of the

exciting field through the values of m and p . The value of A_i is to be computed from standard tables of the confluent hypergeometric function. It is of course noted that these results are based for the most part on approximate solutions of the differential equations which describe the motion.

It should also be noted that for electron oscillations the value of C_e is to be used, and for ion oscillations the value of C_i is to be used. Table 1. Summary of approximate eigenvalue conditions: $B = 2$; $D = r_o^2/2\sigma^2$; where r_o is the plasma radius.

Motion Type	Near Field Variation		Frequency
$R \theta Z$	m	p	
$\sqrt{ } X X$	0	0	$(C/\sqrt{2\pi\sigma})(1-A_i)^{1/2}$
$\sqrt{ } \sqrt{ } X$	0	0	$(C/\sqrt{2\pi\sigma})(1-A_i+\Omega^2)^{1/2}$
$\sqrt{ } \sqrt{ } \sqrt{ } X$	1	0	$-\Omega/2\pi \pm (C/2\pi\sigma)[(3-2A_i)\gamma]^{1/2}$
$\sqrt{ } X \sqrt{ } \sqrt{ }$	0	p	$(\text{fundamental is } \approx -\Omega/2\pi \pm C/\sqrt{2\pi\sigma})$ $-Up/4L \pm [C^2p^2/16L^2 + C^2(1-A_i)/2\pi^2\sigma^2]^{1/2}$

Motion type means:

R , motion component in radial direction;
 θ , motion component in azimuthal direction;
 Z , motion compound in axial direction

MODIFIED SCYLLA DEVICE

A schematic illustration of a conventional Scylla Device appears in the Project Sherwood reference previously cited. See also FIGS. 4a and 4b.

A typical Scylla Device is described in greater detail in an article by F.C. Jahoda, E.M. Little, W.e. Quinn, F.L. Ribe, and G.A. Sawyer, in Journal of Applied Physics, Vol. 35, p. 2351, 1964. For the experiments described in that article the standard deviation of the radial density distribution is approximately 3.3×10^{-2} m. According to that article the circuit used for starting the device is also used for the subsequent operation. Alternatively, the portion of the circuit used for starting is short-circuited after the starting action has been accomplished.

With reference to the device described in the article, for the purpose of the present invention the ion sound speed may be inferred from the ion and electron temperature to be approximately 2.3×10^5 m/sec. Thus the fundamental ion acoustic resonant frequency from row 3, Table 1 with Ω , m , and p equal to zero, would be approximately 1.5×10^6 Hz. The resonant frequency for electron vibrations would be approximately 92×10^6 Hz. According to the present invention the control of the Scylla Device is then provided by the use of another external circuit, in addition to the normal starting circuit.

According to the present invention, the additional external circuit as illustrated in the Decker article men-

30

35

40

50

55

8

onant frequency of this series combination is equal to the fundamental ion acoustic resonant frequency, or approximately 1.5×10^6 Hz. The starting circuit is then used only for starting, and the operating circuit is used only for operating. The additional circuit is then time sequenced with the Scylla starting coil by means of ignition switches which switch the circuit connections at that point of time when it is normal to "crow bar" the driving coil.

Having described the invention, what is claimed as new in support of Letters Patent is:

1. A pulsating plasma device comprising:
means providing a cylindrical plasma column;
at least one field exciter member having substantial length and being supported in spaced parallel relationship to the longitudinal axis of said plasma column and electrically insulated therefrom, said field exciter member having a substantial surface width in a direction generally transverse to the longitudinal axis of the plasma column, the inner surface of said field exciter member facing toward said plasma column being curved in a plane perpendicular to the longitudinal axis of said column;
the curved characteristic of the inner surface of said at least one field exciter member being also constant throughout a substantial length of the field exciter member, the curvature and physical positioning thereof being so selected that the near force field developed thereby is at least approximately proportional to the sine of m times the angle θ ;
here m is an integer which is zero for one field exciter member and the near force field is magnetic, one for two field exciter members, and two for four field exciter members,
and where θ is the angle in cylindrical coordinates in the plane perpendicular to said longitudinal axis; and
electric circuit means coupled to at least said one field exciter member and having an operating frequency related to the physical plasma characteristics in accordance with the following table:

Approximate Eigenvalues

Motion Type	Near Field Variation		Frequency
$R \theta Z$	m	p	f
$\sqrt{ } X X$	0	0	$(C/\sqrt{2\pi\sigma})(1-A_i)^{1/2}$
$\sqrt{ } \sqrt{ } X$	0	0	$(C/\sqrt{2\pi\sigma})(1-A_i+\Omega^2)^{1/2}$
$\sqrt{ } \sqrt{ } \sqrt{ } X$	1	0	$-\Omega/2\pi \pm (C/2\pi\sigma)[(3-2A_i)\gamma]^{1/2}$
$\sqrt{ } X \sqrt{ } \sqrt{ }$	0	p	$(\text{fundamental is } \approx -\Omega/2\pi \pm C/\sqrt{2\pi\sigma})$ $-Up/4L \pm [C^2p^2/16L^2 + C^2(1-A_i)/2\pi^2\sigma^2]^{1/2}$

tioned above, consists of a capacitor and an inductor connected in series, with values so selected that the res-

where $(R, \theta Z)$ are cylindrical coordinates of a coordinate system having its origin on the longitudinal axis of

said column and its Z axis along the longitudinal axis of said column and wherein,

R = the motion component of the plasma in the radial direction,

θ = the motion component of the plasma in the azimuthal direction,

Z = the motion component of the plasma in the axial direction,

m = is an integer which is zero for one field exciter member and the near field is magnetic, one for two field exciter members and two for four field exciter members,

p = an integer,

A_i = the eigenvalue of the confluent hypergeometric function ${}_1F_1(A, B, D)$ where

$B = 2$

$D = r_o^2/2\sigma^2$
